UNITED STATES PATENT OFFICE.

EDWIN ROY GALEBACH, OF LEBANON, PENNSYLVANIA.

COTTER-PIN EXTRACTOR.

1,398,543.

Specification of Letters Patent. Patented Nov. 29, 1921.

Application filed January 13, 1921. Serial No. 436,916.

To all whom it may concern:

Be it known that I, EDWIN ROY GALEBACH, a citizen of the United States, residing at Lebanon, in the county of Lebanon, State 5 of Pennsylvania, have invented a new and useful Cotter-Pin Extractor; and I do hereby declare the following to be a full, clear, and exact description of the invention, such as will enable others skilled in the art to 10 which it appertains to make and use the same.

The invention relates to cotter pin extractors and has for its object to provide a device of this character comprising a pair 15 of pivoted members, said members being pivoted together adjacent one of their ends, which ends terminate in oppositely extending lugs, one of said lugs being adapted to engage in the eye of a cotter pin to be extracted the other lug being adapted to engage a surface adjacent the cotter pin and forming a fulcrum when it is desired to give a twist to the cotter pin when the lug carrying ends of the pivoted members are 20 forced apart during a cotter pin extracting 25 operation.

With the above and other objects in view the invention resides in the combination and arrangement of parts as hereinafter set 30 forth, showing the drawings, described and claimed, it being understood that changes in the precise embodiment of the invention may be made within the scope of what is claimed without departing from the spirit 35 of the invention.

In the drawings:—

Figure 1 is a side elevation of the extractor, showing the same in position for use.

Fig. 2 is in a plan view of the extractor 40 showing the same in position for use.

Fig. 3 is a detail collective view of the jaw ends of the pivoted members.

Referring to the drawings, the numeral 1 designates a bolt and 2 a nut, which nut is 45 held from coming off of the bolt 1 by means of a cotter pin 3, which passes transversely through an aperture in the bolt 1. To remove cotter pins so positioned, it has been found extremely difficult, therefore to obviate this difficulty the extractor tool 4 is provided.

The extractor tool 4 comprises pivoted members 5 and 6 which are pivotally connected as at 7. The ends 8 of the members 55 5 and 6 form handles adapted to be gripped

during a cotter pin extracting operation and when so gripped and forced together the spring 9 is compressed, which spring 9 normally holds the jaws 10 and 11 of the extractor in engagement with each other and 60 closed. Extending outwardly at substantially a right angle with the side of the jaw 10 is a cotter pin engaging lug 12, which lug at its end is provided with a hooked portion 13 which engages in the eye 14 of 65 the cotter pin, said hook preventing the lug from coming out of engagement with the eye 14 of the cotter pin during a cotter pin extracting operation. Extending outwardly from the jaw 11 and from the opposite side thereof to the side which carries the lug 12 is a lug 15, which lug and the jaw 11 engage the nut 2 as shown in Figs. 1 and 2 during a cotter pin extracting operation and by providing a lug 15, a greater 70 leverage is provided when the handle members 8 are forced together for extracting the cotter pin and during which extracting operation, the tool as a whole may be twisted on the lug 15 as a fulcrum point. 80

From the above it will be seen that a cotter pin extracting tool is provided which is simple in construction and one by which cotter pins may be easily and quickly removed, without damaging the pin. It will 85 also be seen that by providing the hooked end 13 on the lug 12 that slipping of the tool during a cotter pin extracting operation is obviated.

The invention having been set forth what 90 is claimed as new and useful is:—

1. A cotter pin extractor comprising a pair of members pivoted together intermediate their ends, the ends at one side of the pivot extending away from each other and forming 95 handles, a spring interposed between said handles, the other ends of said pivoted members forming jaws engaging each other and held in engagement by the spring between the handles, one of said jaws having an outwardly extending arm terminating in a hook adapted to engage in the eye of a cotter pin, the other jaw being provided with a lug extending outwardly from its side and in the opposite direction to the hooked arm of 100 the adjacent jaw, said last named lug forming a fulcrum point for the tool during a twisting operation of the tool, simultaneously with a pin extracting operation.
2. A cotter pin extractor comprising a 110

pair of members pivoted together adjacent one of their ends, a cotter pin engaging lug carried by one of the ends adjacent the pivotal point and extending outwardly from 5 the side thereof, a lug extending outwardly from the end of the other member adjacent the pivotal point in an opposite direction to the cotter pin engaging lug, and spring means for normally holding the ends of the

pivoted members at the opposite ends to the 10 lug carried ends apart.

In testimony whereof I have signed my name to this specification in the presence of two subscribing witnesses.

EDWIN ROY GALEBACH.
